(57) **CLAIM**

The ornamental design for a medication package, as shown and described.

DESCRIPTION

FIG. 1 is a top perspective view of a medication package showing our new design in a folded position;

FIG. 2 is a bottom perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side view thereof;

FIG. 8 is a right side view thereof;

FIG. 9 is a top perspective view of the medication package of FIG. 1 in an unfolded position;

FIG. 10 is a bottom perspective view thereof;

FIG. 11 is a top plan view thereof;

FIG. 12 is a bottom plan view thereof;

FIG. 13 is a front elevation view thereof;

FIG. 14 is a rear elevation view thereof;

FIG. 15 is a left side view thereof; and,

FIG. 16 is a right side view thereof.

The short broken lines in the drawings depict portions of the medication package that form no part of the claimed design.

1 Claim, 6 Drawing Sheets
